LUBRICATING DEVICE

Filed April 1, 1935

UNITED STATES PATENT OFFICE

2,042,206

LUBRICATING DEVICE

Henry A. Brown, Fort Worth, Tex., assignor of
one-fourth to Samuel E. Kennedy, Fort Worth,
Tex.

Application April 1, 1935, Serial No. 14,138

5 Claims. (Cl. 184—21)

My invention relates to a greasing device for tracks, and more particularly to a device for uniformly greasing the guide-rails of elevators.

An object of this invention is to provide a greasing device which may be carried by an elevator, and which will evenly distribute grease on the face and sides of the elevator rails during the movement of the elevator.

Another object is to provide a greasing or lubricating device for vehicle rails which is inexpensive to make and maintain, and which will automatically function to hold the grease against the face and the sides of the rail with an approximately even pressure.

15 An advantage of this invention is that provision is made for elimination of an excessive amount of grease from the rails.

Another advantage is that the device is so constructed as to agitate the grease on the rail when 20 the vehicle is moved.

Other objects and advantages will be fully explained in the following description, and the invention will be more fully pointed out in the claims.

25 Reference is had to the accompanying drawing which forms a part of this application.

Fig. 1 is a side elevation of the device.

Fig. 2 is a vertical section of the same.

Fig. 3 is a plan view of the device.

30 Fig. 4 is a face view of the device, shown in perspective with a portion of the rear wall removed.

Fig. 5 is a rear view of the device, shown with the pressure mechanism removed.

35 Similar characters of reference are used to indicate the same parts throughout the several views.

The device consists of a main housing, preferably formed into an elongated box-like structure and having a bottom 1, side walls 2, and a top 3.

40 Most of the top wall 3 is cut away to permit the installation of a door 4.

It has been found practical to use a hard mass of grease or grease sticks in the lubrication of rails, therefore this device is more particularly

45 adapted to grease with grease of such consistency. In order to facilitate ease of refilling the box-like structure, the door or lid 4 when opened is of sufficient size to expose the whole of the contents of said device.

50 One end of the box-like housing is provided with slots 5 cut into both the top 3 and bottom 1 for fitting around the guide rail of the elevator. These rails 6 are usually formed in a T-shape and the grease must be placed on the face and sides 55 thereof as shown in Fig. 3. This slot 5 is formed

to pass around the rail 6 and in close relation thereto.

Resilient side flaps 7 are hingedly connected, one to each of the side walls 2, and adapted to normally swing inwardly between the upper and lower walls 3 and 1 respectively and against the side of the rail 6, as shown in Fig. 3. Each of these flaps 7 is provided with a coil spring 8 carried on the hinges 9 thereof and adapted to resiliently force the outer edges of the flaps against 10 the side of the rail 6. It is apparent that various forms of resilient means may be used for holding the flaps 7 in operative relation with the rail 6.

Means are provided in the device for agitating the grease, during the movement of the vehicle, 15 so as to insure the desired greasing of the rail 6. This means consists of providing a groove 10 in the inner surface of each flap. This groove 10 may be placed at an angle to the hinge of the flap and serve as a track for that portion of the 20 grease that is forced into the groove. As the pressure is applied to the grease, the groove 10 will guide the same toward the rail at an angle to the travel of the vehicle carrying the greasing device.

25 The rail contacting portion of the device may be termed as the front end thereof, and this end utilizes the rail in conjunction with the flaps 7 and members 1 and 3 to close the same. The rear wall 11 is formed rigid with the members 1, 2 and 3, and extended above the top of the device to form 30 a bearing support for the pressure mechanism used in forcing the grease between the flaps 7 and against the rail 6. The flaps 7 normally resiliently stand with their outer edges against the 35 rail 6, forming a V-shaped entry for the grease, as shown in Fig. 3.

The pressure mechanism for forcing the grease against the rail 6 and flaps 5 consist of a swinging weight arrangement which is constructed to 40 give a continuous pressure to the grease regardless of the amount of grease carried in the device, and of a structure which may be adjusted to give the desired pressure.

45 A block 12 is slidably disposed in the box-like structure of the device and formed to press against the grease placed therein. One end of an arm 13 is pivotally connected to the block 12 and the other end of the arm is pivotally connected to the lower end of the swinging rod 14. The rod 14 is 50 swingingly supported on the rear wall 11 by means of a pivotal connection 15 which connects the top of the rod 14 with the wall 11.

The bar 14 serves as a support for an adjustable weight 16. The weight 16 may consist of a 55

plurality of disks which are carried upon the upper end of a bar 17. The lower end of the bar 17 is rigidly secured to the bar 14 and projected at a slight angle upwardly therefrom. A collar 18 is movably supported upon the upper end of the bar 17 and serves as a base for the disks to rest upon. The disks may be provided with slots or central openings for placing them on the bar 17 and upon the collar 18. When the pressure 10 on the grease is to be varied, the number of disks is either increased or decreased.

The rear wall 11 is provided with a slot 19 for the passage of the arm 13, and the arm 13 is curved to permit the same to function with the 15 swing of the rod 14.

When a stick of grease is inserted through the door or lid 4 into the box-like structure of the device, the block 12 is moved so that its pressure will be exerted against the end of the grease 20 stick opposite the end which contacts with the rail 6. As the grease is applied to the rail, the weight 16 will continue to press the grease stick forward until the grease is completely distributed upon the rail.

25 What I claim is:

1. In a greasing device for rails consisting of a box-like body having slots in the forward end adapted to receive a guide rail, resilient flaps resiliently connected to said body and adapted 30 to normally bear against the sides of said rail for directing grease thereto, a follower block slidably carried in said body for feeding grease toward said rail, and means carried by said body and cooperating with said block for forcing said 35 grease toward the guide rail.

2. In a greasing device for guide rails consisting of an elongated box-like body adapted to contain grease, means for exerting pressure

upon said grease, said body having slots adapted to receive said rail, and resilient flaps carried on said body and adapted to crowd said grease toward said rail.

3. In a greasing device for guide rails consisting of an elongated body adapted to contain grease, one end of said body being slotted to receive said rail, flaps hingedly carried on said body and adapted to project inwardly at an angle to said rail so that the edges opposite their 10 hinges will bear against the sides of said rails and crowd said grease thereto, and means for exerting pressure on said grease for forcing it against said rail.

4. In a greasing device for guide rails consisting of a box-like grease-containing body adapted to be carried by the vehicle upon said rail, one end of said body being slotted to receive said rail, flaps hingedly carried on said body and adapted to normally resiliently crowd 20 said grease toward the sides of said rail, said flaps being provided with grooves adapted to wedge said grease between said rail and said grooves, during the travel of said vehicle, a weight means carried by said body for exerting 25 pressure upon said grease for forcing the same against said rail and between said flaps.

5. In a greasing device for rails consisting of a grease holding body having slots for receiving said rail, resilient flaps carried by said body and 30 adapted to direct said grease against the sides of said rail, said flaps being provided with grooves for guiding and wedging said grease against said rail, and a weight suspended on said body and adapted to force said grease between said flaps and against said rail.

HENRY A. BROWN.
